ATTORNEY

UNITED STATES PATENT OFFICE.

ERNEST W. OPPE, OF NEW YORK, N. Y., ASSIGNOR TO AUGUSTE C. OPPE,
OF SAME PLACE.

MIRROR ATTACHMENT FOR ROW-BOATS.

SPECIFICATION forming part of Letters Patent No. 278,039, dated May 22, 1883.

Application filed November 3, 1882. (No model.)

To all whom it may concern:

Be it known that I, ERNEST W. OPPE, of the city, county, and State of New York, have invented certain new and useful Improvements 5 in Mirror Attachments for Row-Boats, of which the following is a specification.

This invention relates to an improved mirror attachment to row-boats, by which the party rowing can observe directly the objects 10 in the way of the boat without turning his head and looking forward over the bow of the boat; and the invention consists of a row-boat which is provided near the stern with an upright supporting-frame attached to the gunwales, said frame carrying an adjustable mirror 15 with a hood or sunshade applied to the upper part thereof.

In the accompanying drawings, Figure 1 represents a perspective view of a row-boat with 20 my improved mirror attachment, and Fig. 2 is a vertical transverse section of the same.

Similar letters of reference indicate corresponding parts.

A in the drawings represents a row-boat of 25 any suitable construction, and B an upright frame, preferably of yoke shape, which extends transversely across the boat at or near the stern. The frame B is bolted to the gunwales of the boat, and braced by an inclined 30 rod, B', that extends from the highest point of the frame to the keel, to which latter it is securely bolted, as shown in Fig. 2.

A mirror, C, is adjustably supported by

means of pivot-screws b b on frame B, so as to be set into any desired height and inclination 35 as required by the oarsman, according as he desires to look to a greater or less distance forward. A sunshade or hood, D, is applied to the upper part of the mirror to prevent the rays of the sun from falling directly into the 40 glass and be reflected thereby. The mirror attachment forms a great convenience to the oarsman, as he can thereby steer the boat and proceed on his way with great facility without turning his head and looking forward from 45 time to time, as has been the case when rowing without a coxswain heretofore.

Having thus described my invention, I claim as new and desire to secure by Letters Patent—

1. The combination, with a row-boat, of a 50 supporting-frame at or near the stern of the boat, and of an adjustable mirror supported by the frame, substantially as set forth.

2. The combination, with a row-boat, of a 55 supporting-frame arranged at or near the stern, a mirror applied adjustably to the same, and provided with a hood or sunshade, substantially as set forth.

In testimony that I claim the foregoing as my invention I have signed my name in presence of two subscribing witnesses.

ERNEST W. OPPE.
